UNITED STATES PATENT OFFICE.

JAKOB KALMANOVITCH, OF BROOKLYN, NEW YORK.

PHOTO-REPRODUCING APPARATUS.

Application filed October 6, 1921. Serial No. 505,796.

To all whom it may concern:

Be it known that I, JAKOB KALMANOVITCH, a citizen of Russia, residing at Brooklyn, in the county of Kings and State of New York, have invented certain new and useful Improvements in Photo-Reproducing Apparatus, of which the following is a specification.

The principal purpose of the present invention is to provide an apparatus for reproducing photographic copies of pictures in an easy and rapid manner, in any desired number.

A further object is in the provision of a cabinet containing means for feeding the sensitized paper in single sheets from a supply carried therein.

Another object is to provide means for exposing the sheets to the printing effect of light without manual contact and finally, to store the sheets until required.

These and other like objects are attained by the novel construction and combination of parts hereinafter described and shown in the accompanying drawings, forming an essential part of this disclosure, and in which:—

Figure 1 is a partial side elevational, partial sectional view of a photo-reproducing cabinet made in accordance with the invention.

Figure 2 is an enlarged sectional view of the upper portion thereof.

Figure 3 is a detail view of one of the paper transmitters.

Figure 4 is a side view of the cabinet as assembled.

Figure 5 is an enlarged fragmentary sectional view of the exposure chamber.

Figure 6 is a transverse sectional view taken on line 6—6 of Figure 2.

Figure 7 is a perspective view of one of the negative supports.

Figure 8 is a similar view of the mating support.

The cabinet comprises a base section chambered to receive drawers 10 and 11, above which are other drawers 12 and 13 having over them a horizontal partition 14, and at the front, between the wall and the drawer 12, is a narrow drawer 15.

The front wall 16, above the partition 14, is slanted rearwardly and contains two doors, respectively 17 and 18, the lower door 17 being connected by hinges 19 at the bot-

tom and the upper door 18 by other hinges 20 at its side.

The cover plate 21 of the cabinet is engaged by hinges 22 at one side, and the main door 23 at the back has hinges 24 as shown.

Below the cover 21 is a clear space or chamber 25 in which is a movable block 26 mounted on wheels 27 adapted to travel on rails 28, the block being drawn forward, toward the door 18, due to an attached cord 29, passing over a pulley 30 revolubly mounted in the cabinet in front of the block, the cord extending rearwardly over a pulley 31 and then downward to a weight 32.

This weight hangs pendant in a space 33 between the walls of the drawer carrying chambers and the rear door 23, as best shown in Figure 1, and is adapted to pull the block 26 to the front.

Fixed to the end walls of the compartment 25 are slotted guides 34 having sharply bevelled, down turned edges 36 inclined at an angle corresponding with the face of the block 26.

A strip 37, having a bevelled upper edge extends across in angular register with the bar 35, these elements limiting the forward movement of the sheets or cards 38 pressed against them by the block 26.

Immediately in front of the strip 37 is an opening 39 leading to a chamber 40 normally closed by the door 17, rearward of which is a compartment 41 and further to the rear is another compartment 42 containing a drawer 43.

A channelled strip 44 passes across the top of the compartment 40 and a similar but reversed strip 45 is at the bottom, adjacent another space 46 leading to the chamber 47 containing the drawer 15.

The channels of the strips 44 and 45 serve to receive a negative 48 and suspended in front of the negative, on a transverse rod 49 are a pair of opposed frame like elements 50 and 51, having engaging hooks 52 and 53.

Extending from the frame element are arms 54 and 55 containing undercut recesses receptive of the arms 56 and 57 of the oppositely disposed element 51, thus allowing relative adjustment; the arms 56 and 57 are suited to engage the negative 48 and are pressed into position by a block 58 removably engaging the inner surface of the door 17 by hook fastenings as shown.

An electric lamp 59, in the compartment 40 furnishes light to print the sensitized cards, the lamp being provided with a switch (not shown) by which it is controlled.

- 5 The card is pressed against the negative, in addition to the block 59, by a bell-crank lever bar 60 mounted to rotate on a rod 61, the other arm 62 of the bell-crank being engaged with a hook 63 fixed to lower part of
- 10 the door 17 and is normally pressed forward and the door held closed by a spring 64, contacting with the arm 62 of the bell-crank and fastened rigidly at its lower end to the front wall of the chamber 47.
- 15 In order to dispense the cards singly in progressive order from the supply, a pair of shafts 65 and 66 are journaled in the side frames of the cabinet, these shafts being connected by gears 67 and 68 adjacent one of the cabinet walls and the shaft 65 is provided with an extending crank handle 69 by which they are rotated, obviously in reverse directions.

Mounted midway in the length of these shafts are elongated collars 70 and 71 to which are secured pairs of projecting forked heads 72 and 73 carrying pliable contact elements 74 and 75, made of rubber or like material, these elements being 30 pressed outwardly by springs 76 and 77, so as to cause contact with the faces of the cards.

Due to the timing of the gears, the element 75 first engages the outermost card 35 from the stack 38, the contact sufficing to raise the bottom of the card above the bevelled edge of the strip 37, and passing along, permits it to spring back over the bevelled strip, whereupon the upper element 74 40 draws the corresponding edge of the card from below the strip 36 and, in addition to the gravity of the card, urges it to drop through the passage 39 into the compartment 40, where it is adjusted over the negative 48 and the print made.

Eventually the cards, after printing, are received in the drawer 15 and the usual process of developing employed.

Having thus described my invention and 50 set forth the means of its construction, application and use, what I claim as new and desire to secure by Letters Patent, is:—

1. A photographic reproducing apparatus comprising a plurally compartmented cab-

inet, one of the compartments containing a stock of sensitized cards resting at an oblique angle upon their edges, bars having bevelled edges extending transversely in front of the cards, means for raising the lower edge of the cards to pass over the bevelled edge of the lower bar, means cooperative therewith for frictionally actuating the card thereover, a slidable block for pressing the cards against the said bars, a weight controlled means for actuating said block, and mechanical means for releasing the outermost card and for dispensing the same from the compartment.

2. A photographic reproducing apparatus comprising a plurally compartmented cabinet, one of the compartments containing a stock of sensitized cards, a pair of oppositely actuated rollers, means on said rollers for feeding the cards singly from the containing compartment, said means comprising pins fixed in the roller blocks slidable on said pins, wipers set in said blocks and springs encircling said pins adapted to press said blocks outwardly, an adjustable frame 70 removably engaged in another compartment, said frame being adapted to contain a negative, a pressure element for assuring contact of the card with the negative, a printing means in said cabinet, said pressure element being actuated by the door to said 75 compartment in opening and closing the same, and a spring adapted to intercept the card and hold it prior to the operation of said pressure means.

3. A photographic reproducing apparatus comprising a plurally compartmented cabinet, a block having an inclined face movable in the uppermost of said compartments, gravity-operated means for moving said block toward the front of the cabinet, fixed 95 bars having outwardly bevelled edges against which the cards are forced at their upper and lower edges, a pair of shafts mounted in parallel in front of said bars, said shafts being geared together to operate 100 in reverse directions, means for manually rotating said shafts, and pliable, and spring actuated wiper elements carried by each of said shafts in timed relation to engage and dispense said cards singly in progressive 105 relation.

In witness whereof I affix my signature.
JAKOB KALMANOVITCH.
